O. P. SINE.

BLINDING SHIELD FOR ANIMALS.
APPLICATION FILED APR. 14, 1913.

1,099,864.

Patented June 9, 1914.

UNITED STATES PATENT OFFICE.

OLIVER P. SINE, OF COVINGTON, KENTUCKY.

BLINDING-SHIELD FOR ANIMALS.

1,099,864.

Specification of Letters Patent.

Patented June 9, 1914.

Application filed April 14, 1913. Serial No. 760,853.

To all whom it may concern:

Be it known that I, OLIVER P. SINE, a citizen of the United States, residing at Covington, in the county of Kenton and State 5 of Kentucky, have invented certain new and useful Improvements in Blinding-Shields for Animals, of which the following is a specification.

My invention relates to shields for blind- 10 ing animals temporarily while being led.

The object of my invention is to provide a shield which is simple in construction, inexpensive to manufacture and one which can be quickly placed on the animal's head, cov- 15 ering the eyes to form an efficient means for blinding said animal when it is desired to lead it from a burning building or the like.

While the device is intended to be used especially in cases of fire it may readily be 20 used on animals whenever there is danger of them becoming panic stricken or frightened.

My invention consists in the certain parts, combination of parts and details of construction as will be described in the following specification and pointed out in the appended claims.

In the drawings: Figure 1 is a view of my improved shield looking at the front of same. Fig. 2 is a cross sectional view taken 30 through the center of the device. Fig. 3 is a perspective view of the device. Fig. 4 is a fragmentary detail view of the wire frame employed which constitutes the frame of the device. Fig. 5 is a cross section taken on the 35 line 5—5 of Fig. 1.

Referring more particularly to the drawings 1 represents the wire frame which is bent at the top thereof to form a fore-top loop 1' or a looped portion adapted to sur- 40 round the fore-top of the animal upon which the device is mounted. The wire frame is also provided with loops 2 and 3 at the sides thereof to form fastening means for the adjustable strap or fastening means 4, for 45 holding the device in position on the animal's head.

The wire frame 1 is preferably shield shaped as illustrated and is particularly adapted for use on horses although with 50 very slight changes in the shape only, it could readily be adapted for use on most any animal.

The wire frame 1 has mounted thereon the web portion 5 preferably felt. This

web portion is bound to the wire frame by a 55 band of suitable material 6 which surrounds the wire frame and is stitched or fastened in any suitable manner to the felt suitable openings in the band being provided for the loops 2 and 3. 60

To give the device the proper strength and stiffness the stiffening member 7 is provided which is preferably constructed of wood. This stiffening member 7 is placed on the outside of the felt web portion and a 65 covering of leather 8 is placed thereon. This leather covering is stitched to the felt along the sides of the stiffening member 7 passing over the binding 6 preferably at the ends as shown in the drawing. 70

The leather covering 8 is provided with slots 9 adjacent the middle of the device in which a handle portion 10 is inserted which is preferably made of a coarse cloth of sufficient strength to be practical. This handle 75 is riveted to the stiffening member 7 through the leather covering 8 by rivets 11.

The wire frame 1 is preferably made of one piece of wire joined at the bottom as illustrated in Fig. 4. The joint is covered 80 by the sleeve 12 which forms a secure joint for the wire.

A strap 13 is provided and is adapted to be fastened to the loops 2 and 3 at the sides of the frame 1 by means of the snap hooks 85 14. The strap is preferably adjustable to different lengths to accommodate animals with different size heads. The adjustability of the strap may be accomplished in the customary manner as shown, preferably by 90 the traveling clamp 15 to which one end of the strap is attached.

The entire device is so simple in construction that it can be made with very little expense and therefore a number may be provided, preferably one for each animal in the building with but little cost to the owner. 95

The device when being mounted is grasped by the handle 10 and is placed over the animal's eyes and then the strap 13 is passed 100 around the under side of the animal's jaw and fastened to the loop 2 on the other side of the device. If the device is properly positioned the loop 1' will surround the fore-top of the animal and thereby hold the device in proper position on the animal's head. 105

It will be understood that certain modifications of my invention might be made with-

out departing from its spirit and scope and I do not wish to be confined to the exact details shown.

What I claim and desire to secure by Letters Patent is:

1. A device of the character described comprising a wire frame, a web portion mounted thereon, loops formed in said wire frame at the sides thereof, an extension at 10 the top of said frame adapted to fit the fore-top of an animal, and a strap adapted to be fastened to said loops on said frame for maintaining said frame in position on the animal's head.

2. A device of the character described 15 comprising a wire frame joined at the bottom, a sleeve covering said joint, a web portion on said frame, an extension at the top of said frame curved to fit the fore-top of an animal, loops at the sides of said frame, a 20 strap adapted to fasten to the sides of said frame and in said loops and a handle on the front of said web portion substantially as set forth.

OLIVER P. SINE.
